UNITED STATES PATENT OFFICE.

HAROLD J. CARMODY, OF BROOKLYN MANOR, NEW YORK, ASSIGNOR OF ONE-HALF TO
JOSEPH A. FAUROT, OF NEW YORK, N. Y.

VALVE MECHANISM FOR INTERNAL-COMBUSTION ENGINES.

1,378,093.

Specification of Letters Patent. Patented May 17, 1921.

Application filed June 29, 1918. Serial No. 242,517.

To all whom it may concern:

Be it known that I, HAROLD J. CARMODY, a citizen of the United States, residing in Brooklyn Manor, in the county of Queens 5 and State of New York, have invented certain new and useful Improvements in Valve Mechanisms for Internal-Combustion Engines, of which the following is a full, clear, and exact description.

10 My invention relates to internal combustion engines, and more particularly to the valve mechanism therefor and the means for actuating the valve mechanism.

More particularly stated, I seek to increase 15 the general efficiency of the engine by improving the lubrication and rendering certain parts more readily accessible, as well as more easily adjusted.

This application is closely associated with 20 my copending application, Serial No. 230,875, filed April 26, 1918, for patent upon an internal combustion engine.

Reference is made to the accompanying drawing forming a part of this specification, 25 and in which like reference characters indicate like parts throughout the several figures.

Figure 1 is a side view, partly in section and partly in elevation, of a four-cylinder internal combustion engine embodying my 30 invention.

Fig. 2 is a view of a detail of a portion of the valve actuating mechanism.

Fig. 3 is a detail view, partly in section, 35 of a roller wheel which may, if desired, be substituted for the spur wheel shown in Fig. 2 as a part of the valve actuating mechanism.

Fig. 4 is a side elevation of one of the two revoluble valve sleeves, and parts immediately associated therewith.

40 Fig. 5 is a side elevation of the other of the two revoluble valve sleeves, and parts accompanying the same.

Fig. 6 is a detail of construction of the valve head.

45 Fig. 7 is a view of the spiral cam forming a part of the valve actuating mechanism.

Fig. 8 is a view, partly in perspective and partly in section, of the cylinder head and the valve mechanism associated therewith.

50 Fig. 9 is a perspective of the cylinders, which in this instance are cast *en bloc*,

Fig. 10 is a diagrammatic perspective of another form of construction, in which the rotary valve sleeves are located at the sides of the cylinders. 55

Fig. 11 is a fragmentary side elevation of the lubricating system of the engine.

Fig. 12 is a perspective detail of a valve carrier which may form a part of the casing.

Fig. 13 is a substantially central section 60 through the revoluble valve sleeve shown in Fig. 5.

The particular mechanism here illustrated is a four cycle, four cylinder internal combustion engine, the cylinders being shown at 65 14, 15, 16, 17, and cast *en bloc*.

Working in these cylinders are pistons 18, 19, 20, 21, which by means of connecting rods 22, 23, 24, 25, communicate rotary motion to the crank shaft 26. The cylinders 70 and the crank shaft are inclosed by a casing 27 in the usual or any desired manner, the casing being provided with passages 28^a, and thus having water jackets about the cylinders for cooling purposes. 75

An intake port 28 and an exhaust port 29 are provided for each cylinder. These ports communicate through the valve mechanism with the intake manifold 30 and with the exhaust manifold 31, respectively. 80

In Fig. 1 of the drawings is shown a valve casing member 32, having generally a cylindrical form, and extending longitudinally across the tops of the cylinders. This casing member is provided with ports 33 and 34, 85 arranged in pairs as shown, one pair for each cylinder, so that each port 33 is always in registry with a port 28, and each port 34 is always in registry with a port 29.

The valve casing 27 is secured to the cylinder head in any suitable manner, as shown for instance in Fig. 6, by bolts 35 extending through flanges 36 and 37, the flange 36 being integral with the casing 27, and the flange 37 being integral with the casing member 32. 90

Mounted within the valve casing member 32 are two revoluble valve sleeves 38, 39, each having substantially the form of a cone frustum with slight taper. The mean diameter of the sleeve 39 is a little less than that of the sleeve 38, so that the sleeve 39 100

fits into the sleeve 38. Thus the sleeves 38, 39 fit each other concentrically.

The sleeve 38 is hollow, and is provided with a number of ports 40, each being essentially a slot. The ports 30 are arranged in pairs, one pair for each of the engine cylinders. Each of these pairs is staggered relatively to the other pairs, as may be understood from Fig. 4.

10 The valve sleeve 38 fits so neatly into the valve casing member 32 as to make almost an oil-tight fit even when the sleeve is turning. The valve sleeve 38 carries a number of packing rings 38^a, each encircling it and being sunken slightly into its outer surface. These packing rings are of spring steel, and are each provided with a pair of holes 38^b. These holes are always in registry with ports 38^c, with which the valve sleeve 38 is provided. Each packing ring is anchored to prevent it from being displaced relatively to the valve sleeve 38, as the latter turns.

The valve sleeve 39 is somewhat longer than the valve sleeve 38, and the two sleeves are so proportioned that when fitted together and mounted in position as above described they may be rotated in opposite directions.

30 The valve sleeve 39 is provided with a number of ports 40^a, each extending diametrically through it and having a rectangular cross section. Each port 40^a is staggered relatively to the others, as may be understood from Fig. 13.

35 The parts in each of the revoluble valve sleeve 38 and 39 are so positioned that at predetermined moments of time a port of one valve sleeve will register with a port in the other, thus forming passageways 40 through the valve members for the passage of gases therethrough, and thus for the moment permit the gases to flow into or out of the cylinders, while at other times these passages are closed. Thus the intake manifold 30 and the exhaust manifold 31 are each periodically brought into momentary communication with each cylinder, and as between the several cylinders this action takes place in a definite order of succession.

50 The operation of the valve sleeves 38 and 39, and consequently the opening and closing of the cylinder ports, is effected and synchronized with the revolution of the crank shaft and with the positions of the pistons in the cylinders of the engine, by means of a spiral wheel comprising a thread 42 carried on a disk 43. This disk is mounted rigidly upon the crank shaft 26, and is revoluble therewith. The thread 42 meshes a spur gear 44, which is rotated by the thread as the disk 43 turns with the crank shaft. If desired, a gear 44^a, provided with roller teeth 44^b, as shown in Fig. 3, may be substituted for the spur gear 44.

The rotation of the spur gear is comparatively slow as compared with that of the crank shaft, the spur gear making one complete revolution to four revolutions of the crank shaft, and is a so-called step-by-step 70 movement. This movement is rendered variable by the form of the thread 43. That is, the thread is distorted from a normal spiral.

The spur gear 44 is mounted rigidly upon 75 a shaft, which extends vertically as shown in Fig. 1, and carries upon its upper end a bevel gear 46.

The valve sleeve 38 is provided with a bevel gear 47, and the valve sleeve 39 is provided with a bevel gear 48. The bevel gears 47 and 48 engage opposite sides of the bevel gear 46, so that rotation of the gear 46 causes the gears 47 and 48 to rotate in opposite directions.

80 The valve gearing is mounted in a casing 49, with which the cylindrical casing member 32, above described, is integral. The valve casing 49 is secured to the cylinder casing 27 by bolts 50, as indicated in Fig. 1, and is so formed as to provide a bearing 90 for the shaft 45. The casing 49 is further provided with a removable casing head 51, normally held in position by bolts 52. By removing the casing head 51 the valve 95 mechanism is rendered accessible for purposes of inspection, removal and replacement.

85 The casing head 51 carries a threaded center bolt 53, and mounted upon this bolt 100 is a lock nut 54 for locking it in position upon the casing head. The center bolt is pointed, and fits into a head 55 with which the sleeve 39 is provided, at the end thereof adjacent the bevel gear.

105 The valve sleeve 39 is provided with a threaded portion 56, and adjustably fitted upon this threaded portion is a collar 57. By turning this collar relatively to the sleeve 39, it is adjusted. The collar 57 110 abuts against the adjacent face of the bevel gear, so that each of the abutting surfaces is a bearing surface for the other, and is also a limiting stop therefor. Thus the bevel gears 47 and 48 can not approach each 115 other beyond a limit determined by the position of the collar 57 upon the sleeve 39.

Another center bolt is shown at 58, and carries a lock nut 59. This bolt 58 is threaded, and extends through a threaded passage in the adjacent end of the cylindrical valve casing member 32. This center bolt 120 engages the end center of the sleeve 38, and serves both as a bearing and as an adjustment for the valve sleeve.

125 By turning the center bolts 53 and 58 the valve sleeves 38 and 39 are adjusted relatively to each other and to the valve casing so as to compensate for wear.

Below the vertical shaft 45 is another cen- 130

ter bolt 60, which carries a lock nut 61 and extends through a threaded hole in the casting 27. This center bolt engages the lower end of the shaft 45 and serves as a bearing for this shaft. By turning the center bolt 60, the shaft 45 and parts carried by it are raised or lowered to a slight extent.

While each center bolt 53, 58 and 60 is adjustable independently of the others, any two of these bolts, or all three of them, may be adjusted interdependently. If in adjusting one of them the adjustment of another is disturbed, it can be corrected by moving the other. For instance, if the bolt 53 be turned so as to move the gear 48 to the right and the bolt 58 be so turned as to move the gear 47 to the left, according to Fig. 1, this may cause the gears 48 and 47 to crowd the gear 46. This could be corrected by turning the bolt 60 so as to lower the shaft 45, and with it the gear 46. Again, it might happen that, owing to excessive wear upon the teeth of the various bevel gears, each bevel gear might be loose relatively to the others, yet the valve sleeves might need no adjustment. In such event the screw 60 should be turned so as to lift the shaft 45 a slight distance. This would obliterate the looseness just mentioned, and would not disturb the valve sleeves.

The ports in the valve sleeves 38 and 39 are so distributed, and the valve members are together rotated at such variable speeds, that at predetermined moments each cylinder in succession will be first in communication with the intake manifold and then with the exhaust manifold, and that at definite intervals each cylinder will be cut off from all communication with either manifold, and will so remain for a momentary but predetermined interval of time.

In the present embodiment the rotation of the valve sleeves for the purposes just stated is effected, and the rotation of the valve sleeves is synchronized with that of the crank shaft, by means of the spiral cam 42 and spur gear 44 above described. The form of the spiral cam 42 is indicated in Fig. 7, and is a factor in the attainment of proper synchronization. Other factors in this synchronization and in the movements of the revolute valve sleeves are the number of teeth on the spur wheel 44, and the size of the bevel gear 46 as compared with that of the two bevel gears 47, 48.

By properly proportioning the gears and shaping the spiral cam 42 accordingly, the parts may be so arranged that with the device in action the inlet ports are brought into and out of registry, and the exhaust ports brought into and out of registry, at suitable time intervals for a four cycle action.

By this arrangement of the valve sleeves a quick opening and closing of the ports is

obtained, and upon this account it is permissible to make all of the ports rather large as compared with the size of the cylinders. This insures the easy flow of the gases into and out of the cylinders, and has other advantages well recognized in this art.

Fig. 8 shows a form of my rotary valve mechanism built into and forming a part of a removable cylinder head, the cylinder block associated with this cylinder head being shown in Fig. 8. This arrangement of the parts offers a practical and efficient means for modifying many multiple cylinder engines of standard construction so as to incorporate rotary valve mechanism therewith instead of valve mechanism using the ordinary poppet valves, the engines thus modified acquiring all the advantages of an engine fitted with the rotary valve mechanism above described.

In the form shown in Figs. 8 and 9 the cylinder block appears at 63, and in this instance is water-jacketed. The inlet pipe for the water is shown at 64, and is used for connecting the water passages 65 with the radiator in the usual or any desired manner. Holes 66 in the cylinder block are provided for receiving bolts 67, the latter being used to hold the cylinder head in position upon the cylinder block.

The cylinder head, which is of the multiple type, is shown at 68 and comprises the water jacket construction, having water passages 69 adapted to register with the water passages 65 in the cylinder block. The multiple head is provided with bolt holes 70 for receiving the bolts 67, in order to enable the cylinder head to be secured in position.

The cylinder head is provided with a substantially cylindrical portion 71, which is formed into a water jacket and serves as a casing member for the revolute valve sleeves above described. A passage 72, having a general cylindrical shape, communicates freely with the water jacket in the cylinder head. Within the cylindrical casing member 71 are the revolute valve sleeves 38, 39 above described, and provided, respectively, with bevel gears 47, 48, the latter meshing with and driven in opposite directions by the bevel gear 46.

The cylinder head is provided with explosion chambers 73, and merging into each of these explosion chambers is an inlet port 74 and an exhaust port 75. The inlet ports 74 and exhaust ports 75 correspond in function and character to the ports 28 and 29 shown in Fig. 1 and above described. A pipe connection 76 is for use in circulating water through the water jacket of the cylinder head.

The cylinder head and valve casing shown in Fig. 8 may, if desired, be cast in a single integral block, as shown. These parts may be incorporated in the engine construction.

as originally built, or they may in many instances be substituted for removable heads of other types.

Instead of arranging the revoluble valve sleeves as above described, they may be supported in a tubular valve carrier 77, having the form shown in Fig. 12. The valve carrier 77 is an elongated casing member, the inner surface of which serves as a bearing 10 surface for a revoluble valve sleeve 38^a, of the proximate form of the revoluble valve sleeve 38, above described. Revolubly fitting into the valve sleeve 38^a is another valve sleeve 78, having the form shown more particularly in Fig. 13. This valve sleeve is hollow, and is provided with a closed end 79. Its opposite end 80 is provided with a port 81, substantially coaxial with the sleeve, and used for introducing lubricating oil thereinto. This port also serves to accommodate the centering pin and thus acts as a bearing.

The valve carrier 77 is provided with a number of inlet ports 82 and with a number of outlet ports 83, and the valve sleeve 78 is also provided with ports 84 and 85. These ports consist of diametrically disposed pipes 86, which seal the ports 84 and 85 from communication with the interior of the tubular sleeve, as indicated in Fig. 13.

30 The valve sleeve 38^a is provided with pinholes 87, serving as oil ducts by aid whereof lubricating oil is distributed. The valve sleeve 78 is similarly provided with pinholes 88, which communicate with the interior of the sleeves, and are adapted to convey oil in between the valve sleeves, whence it finds its way through the oil ducts 87 and in between the revoluble sleeve 38^a and the inner surface of the valve carrier 77.

40 As may be seen from Fig. 1 the revoluble valve sleeves are completely inclosed within the casing, so that the gearing used to operate the valve members may be completely housed and enabled to run in the lubricating oil.

The valve sleeve 78 carries a bevel gear 89, having a similar form and purpose to that of the bevel gear 47 above described.

In some instances I employ a centrifugal 50 oil pump 90, driven directly by the crank shaft 91, as shown in Fig. 11. The supporting portion 92 of the casing 49 is provided with an oil duct 93, merging into a passage 94. From this passage a pipe 95 leads to the pump 90.

60 In all forms of my device the oil, after lubricating the revoluble valve sleeves, is collected and returned through a passage 27^a, shown at the right of Fig. 1, and preferably cast in the casing as a void.

The centrifugal pump 90 forces the lubricating oil up through the passage 94 so as to fill the upper portion of the casing 49 and thus wholly or partially submerge the bevel 65 gears. The oil finds its way into the valve

sleeve 78, through the hole 81, thence passes radially outward through the pinholes, and works in between the inner and outer valve sleeves, thence passes outwardly through the pinhole ducts of the outer valve sleeve, and at last works out into the passage 27^a (see Fig. 1) and into the crank casing. Here it is again taken up by the centrifugal pump.

70 Referring more particularly to Fig. 13 it will be noted that the port 81 is so located that when the device is in action as shown in Fig. 11, a considerable volume of oil in free form is contained at all times within the valve sleeve 78. Such being the case, if for any cause the supply of lubricating oil into 80 the inner valve sleeve happens to be cut off, the sleeve must still retain a considerable volume of free oil. This volume of free oil is thus virtually an auxiliary oil supply, insuring adequate lubrication even in the event 85 of accident to the pump or parts immediately associated therewith.

Referring again to Fig. 13, it will be noted 90 that the valve sleeve 78 is provided with a number of webs 95, preferably integral with it as shown. These webs are each of substantially annular form, and they are spaced apart at intervals along the sleeve. Each web is adapted to serve as a dam or embankment for holding a body of lubricating oil 95 in the event that the flow of oil into the sleeve is cut off, as above described. Moreover each web is so arranged as to retain a considerable portion of such body of oil even when the sleeve is inclined slightly in the 100 direction of its length. By this arrangement, even if the engine be tilted within considerable limits a number of separate volumes of oil will remain within the sleeve and available as a reserve supply, so that the 105 tilting of the engine even for considerable periods of time can not interfere with proper lubrication.

110 The valve carrier 77 is provided with flanges 96, having bolt holes 97 for convenience in fastening the carrier alongside the several engine cylinders in proper position so that the inlet and exhaust ports shall register with the similar ports in the several cylinders. By this arrangement many forms 115 of engine, having valve operating mechanisms of a widely different character from that herein disclosed may be supplied with the revoluble valve sleeves and valve operating mechanism. In such instances all that is 120 required is to remove the usual valves and fasten the valve carrier 77 in position alongside the cylinders, as above described. The inlet manifold may be mounted as shown at 98, and the exhaust manifold as at 99, in 125 Fig. 10.

130 Although many advantages result from the association of the revoluble valve sleeves as above described with the particular form of gearing herein disclosed for transmit-

ting motion thereto from the crank shaft, it will be understood that the invention is not limited to the special type of transmission mechanism disclosed, but that other forms may be employed instead.

As many changes could be made in the construction above described, and many different embodiments of this invention could be made without departing from the scope thereof, it should be understood that the foregoing description and the accompanying drawings are merely illustrative and not as limiting the scope of the invention.

I claim:

- 15 1. In an internal combustion engine the combination of a revoluble valve sleeve, a gear wheel mounted upon said valve sleeve for turning the same, a second valve sleeve fitted into said first mentioned valve sleeve, a collar mounted upon said second mentioned valve sleeve and adjustable relatively thereto, said collar being abutted by the end of said first mentioned valve sleeve, a gear wheel carried by said second mentioned valve sleeve, and means common to the gear wheels for turning the same in opposite directions.
- 20 2. In an internal combustion engine the combination of a revoluble valve sleeve provided with ports, a second revoluble valve sleeve provided with ports adapted to be brought into and out of registry with said

first mentioned ports, a collar carried by said second mentioned valve sleeve and adjustable relatively thereto, said collar being 35 normally abutted by the adjacent end of said first mentioned sleeve.

3. In a valve mechanism for internal combustion engines the combination of a valve casing member having generally the 40 form of an elongated sleeve and provided with a closed end, a pair of revoluble valve sleeves located within said casing member and one disposed concentrically to the other, said sleeves being provided with pin holes 45 for discharging lubricating oil between said sleeves so that said oil gradually escapes into said valve casing member, a source of supply of said oil, and means for returning said oil from said valve casing member to 50 said source of supply.

4. In a valve mechanism for internal combustion engines the combination of an elongated valve casing member provided with ports, a pair of valve sleeves located within said casing member and disposed concentrically one within the other, each of said valve sleeves having ports for coacting with said first-mentioned ports, the innermost of said sleeves being provided with 55 pin holes for distributing oil to the outermost of said sleeves, and means for admitting oil into the innermost of said sleeves.

HAROLD J. CARMODY.
